FIG. 7. John Waldheim
By Jacob Falter
His ATTORNEY

UNITED STATES PATENT OFFICE.

JOHN WALDHEIM, OF NEWARK, NEW JERSEY, ASSIGNOR TO UNION TYPEWRITER COMPANY, OF ILION, NEW YORK, A CORPORATION OF NEW YORK.

TYPE-WRITING MACHINE.

1,012,943.

Specification of Letters Patent. Patented Dec. 26, 1911.

Application filed November 14, 1910. Serial No. 592,218.

To all whom it may concern:

Be it known that I, JOHN WALDHEIM, a citizen of the United States, and resident of Newark, in the county of Essex and State 5 of New Jersey, have invented certain new and useful Improvements in Type-Writing Machines, of which the following is a specification.

My invention relates to typewriting machines and more particularly to carriage feed or escapement mechanism.

The present invention is in the nature of an improvement on the constructions disclosed in the three applications of Charles 15 H. Shepard Serial Nos. 591,679; 591,680 and 591,681.

This invention has some of the same general objects in view as the inventions disclosed in the said Shepard applications; 20 namely, to provide an easily operated, efficient and reliable escapement mechanism and one in which the wear of the escapement devices is greatly reduced; the construction in the present instance being such that each 25 complete operation of a finger key moves the dog rocker in but one direction.

A further object of the invention is to provide simple and efficient adjusting means by which the timing of the "let-off" of the 30 carriage can be nicely regulated.

To the above and other ends which will hereinafter appear, my invention consists in the features of construction, arrangements of parts and combinations of devices 35 to be hereinafter described and particularly pointed out in the appended claims.

In the accompanying drawings wherein like reference characters represent corresponding parts in the various views, Figure 40 1 is a fore and aft, vertical, central, sectional view of one form of typewriting machine embodying my invention. Fig. 2 is a diagrammatic side elevation with parts in section, showing one of the key levers, the 45 double universal bar and the means carried by the key lever by which the universal bar is actuated. Figs. 3 and 4 are like views of the same showing the parts disposed in different positions. Fig. 5 is a detail rear elevation, with parts in section, of the escapement mechanism. Fig. 6 is a side elevation 50 of the same with the parts in section. Fig. 7 is a fragmentary diagrammatic view of the feed dog and escapement wheels. Fig. 8 55 is a rear elevation, with parts in section,

showing a modified form of escapement mechanism. Fig. 9 is a side elevation of the same with parts in section.

I have shown my invention embodied in the present instance in a No. 10 Remington 60 machine, although only a conventional representation of the carriage appears in the drawings. It should be understood, however, that the invention may be embodied in various styles of typewriting machine. 65

The frame of the machine comprises a base 1, corner posts 2 and a top plate 3. Key levers 4 are fulcrumed at their rear ends on a fulcrum bar 5 and are each provided with a finger key 6 and a returning spring 7. 70 Each key lever is connected to an upwardly extending link 8, connected at its upper end to a sub-lever 9, pivoted at 10 to a hanger 11. The rear end of each sub-lever 9 is connected to a link 12 which in turn is connected at its rear end to a type bar 13, pivoted at 14 to a hanger 15. The type bars 75 are segmentally arranged to strike upwardly and rearwardly against the front face of a cylindrical platen 16 carried by a carriage 17. The carriage comprises front and rear oppositely grooved guide rails 18 which receive anti-friction balls or rollers 19, which rollers are likewise received in oppositely grooved fixed guide rails 20, secured to upwardly extending lugs 21 on the top plate of 80 the machine. The carriage is thus mounted for movement from side to side of the machine over the top plate, the carriage being moved from right to left by the usual spring 85 drum 22, shown in dotted lines because it is located on this side of the plane on which the section is taken in Fig. 1. Upwardly extending lugs 23 project from the rear of the carriage near the ends thereof. Rearwardly projecting arms 24 are pivoted at 90 25 to the lugs 23 and these arms are connected at their rear ends to a feed rack 26, which meshes with a feed pinion 27, fixed to the forward end of the shaft 28, mounted 95 to turn in a bearing 29, fixed to the top plate of the machine. The rear end portion of the shaft 28 extends beyond the bearing 29 and has a collar 30 secured thereto by a set screw 31. Projections 32 extend rearwardly from said collar parallel with the axis of the escapement wheel shaft 28. 100 These projections 32 extend into corresponding slots 33 in the hub of an escapement rack or wheel 34. 105

From an inspection of Fig. 6 it will be seen that the shaft 28 has an exteriorly threaded hollow spindle or sleeve 28^a loosely mounted thereon; the threads 35 and 36 on the sleeve extending in opposite directions to constitute right and left-hand screw threads. The hub of the escapement wheel 34 is interiorly threaded to coöperate with the screw threads 36 whereas a corresponding hub 37 on a second escapement wheel 38 is interiorly threaded for coöperation with the threads 35. The threaded sleeve 28^a is extended rearwardly beyond the threads 35 to form a bearing portion 39 on which a sleeve 40 is mounted. This sleeve is knurled on its periphery to form a finger piece by which the threaded sleeve may be turned, as will hereinafter more clearly appear. The sleeve 40 is provided with an inwardly extending pin 41 which is received in a splined groove 42 in the extension 39 of the threaded sleeve. The splined connection between the finger piece 40 and the threaded sleeve 28^a is merely to facilitate an assembling or dis- 25 mantling of the parts. Thus a collar 43 is fixed to the rear end portion of the shaft 28 by a set screw 44. When this collar is detached the finger piece 40 may be removed to enable the sleeve or hollow-spindle 30 28^a together with the escapement wheels 38 and 34 to be removed from the shaft 28. The wheels may then be taken off the sleeve 28^a by threading them off said sleeve in opposite directions. Screws 45 are received 35 in and pass freely through openings in the escapement wheel 38, and are adapted to be received in threaded openings in the escapement wheel 34 when the parts are positioned as represented in Fig. 5, so as to fix the escapement wheels, or two members of the double escapement wheel, to rotate together.

From the foregoing description it will be understood that the collar 30 is fixed to the shaft 28, and that the escapement wheel 34 is fixed, through the connection 32-33, to rotate with said collar, and the escapement wheel 38 being connected to the escapement wheel 34, all of these parts will rotate together. The teeth of the escapement wheels are spaced apart, and so disposed, that a movement of the double escapement wheel 34-38 from a tooth of one of said wheels to the next on-coming tooth of the other wheel, affords a full letter space movement of the carriage. It will also be understood from the foregoing description that a turning of the finger piece 40, when the screws 45 are loosened, will effect a relative adjustment between said escapement wheels toward and away from each other. After a relative adjustment of the wheels has been effected the screws 45 should be tightened to bind the wheels together. The purpose of 65 this relative adjustment of the wheels is to

regulate the timing of the "let-off", as will hereinafter more clearly appear.

A single feed dog 46 is pivoted at 47 to a dog rocker 48. The dog 46 is received in a slot in the dog rocker and the tail 49 of the dog bears against the body portion of the dog rocker to limit the movement of the dog in one direction. A coiled expansion spring 50 is received in a recess in the dog rocker and bears at its upper end against the feed dog to the right of the pivot 47, as the parts are shown in Fig. 5. The pressure of the spring 50 is thus exerted to normally maintain the feed dog 46 in the elevated position and in the path of the teeth on the escapement wheel which is in the plane of the feed dog. The dog rocker 48 has a rock shaft 51 mounted at its ends on coned pivot screws 52, received in tapped openings in lugs 53, which latter project rearwardly from a bracket plate 54 secured to the top plate of the machine and depending therefrom. A downwardly extending arm 55 is apertured to receive the rock shaft 51 of the dog rocker. The arm 55 is adapted to receive a pivotal adjustment around the rock shaft 51 by means of an adjusting device which comprises an eccentric 56, the bearing spindle 57 of which is adapted to turn in a bearing portion 58 on the dog rocker 48. The spindle 57 is provided with a finger piece 59, in the nature of a knurled head, by which the spindle and the eccentric 56 may be turned. The eccentric is received in a rectangular opening 60 in the arm 55, the width of the opening corresponding to the diameter of the eccentric 56. By turning the finger piece 59 the dog rocker may be turned relatively to the arm 55 either to the right or left, as the parts are shown in Fig. 6, thus affording a relative adjustment between the dog rocker and the depending arm 55. The lower end of the arm 55 is connected to a link 61 which has its forward end pivoted at 62 to an upwardly extending crank arm 63, fixed to a rock shaft 64. This rock shaft is mounted to turn in suitable bearings in the base of the machine and is provided with forwardly projecting crank arms 65 near the ends of the rock shaft. To these arms is fixed a universal bar 66, which extends transversely of the machine beneath the system of key levers 4. Crank arms 67, corresponding to the crank arms 65, project rearwardly from the rock shaft and support a universal bar 68 which likewise extends beneath the system of key levers 4. The two universal bars 66 and 68 are thus connected to the rock shaft 64 to move in unison but to move in opposite directions. From certain aspects of the invention therefore the two connected universal bars may be regarded as a double universal bar. From other aspects the universal bars 66 and 68 may be regarded as two universal 130

bars, each operated by its own independent mechanism; as will hereinafter more clearly appear.

Screw stops 69 are received in tapped openings in lugs 70 on the base of the machine and are adapted to coöperate with and limit the downward movement of the universal bar 66, whereas corresponding screw stops 71 are adapted to coöperate with and limit the downward movement of the universal bar 68. Each of the key levers 4 carries actuating devices by which first one and then the other of the two universal bars 66 and 68 may be actuated at successive key strokes, so that the universal bars are alternately actuated at successive down strokes of the key. In the present instance these actuating devices comprise pawls 72 and 73, pivoted at 74 to the associated key lever at opposite sides of the rock shaft 64; two of such pawls being carried by each of the key levers. A leaf spring 75 has central depending ears 76 by which the spring may be connected by a rivet 77 to a key lever. The opposite free end portions of each leaf spring are adapted to bear on the top flat ends 78 of the pawls, and tend to maintain the pawls fixed relatively to the key lever, to which they are connected, in the positions shown in Fig. 1. Each of the pawls 72 and 73 is provided with an engaging notch 79 and an engaging face 80 for purposes which will hereinafter more clearly appear. Each of the universal bars 66 and 68 is preferably formed with a sharp upper engaging edge 81 for engagement in the notches 79 of the pawls 73 and 72 respectively, on the different key levers, whereas the engaging face or projection 80 on each of the pawls is adapted to co-act with the associated universal bar, under certain conditions, as indicated in Fig. 2 for example.

It will be understood that the dog rocker and the entire train of connections from the feed dog to the universal bars is free from spring pressure, or from a spring pressure which tends to move the parts from the positions to which they may be moved under control of the finger keys. In other words, the parts are free to remain in the positions to which they are moved by the finger keys at each operation thereof, and in the actuation of the escapement mechanism it is unnecessary to overcome the power of returning springs, such as are ordinarily used to return the dog rocker, universal bar, etc., to normal position; the only returning springs employed in the present instance being the returning springs 7 for the key levers themselves and the light springs 75 for the pawls 72 and 73. Moreover, it will be understood that a full letter space movement of the carriage is effected at each back or forth movement of the dog rocker, or at each movement of the

feed dog from one escapement wheel to the other transversely of the plane of the escapement wheels, and by a movement of the feed dog in but one direction.

Referring to Fig. 1 it will be seen that a depression of any of the key levers 4 is effective to carry the associated pawl 72 carried thereby into engagement with the universal bar 68. A continued downward movement of the finger key is effective to depress the universal bar to the position shown in Fig. 2, thereby rocking the rock shaft 64 and crank arm 63, effecting a rearward longitudinal movement of the link 61 to turn the dog rocker on its rock shaft, thus moving the feed dog forwardly out of engagement with the rear escapement wheel 38 and carrying it into the path of the next oncoming tooth of the escapement wheel 34. This affords a full letter space movement of the carriage on a down stroke of a key and provides a "reverse" escapement. At the termination of the first down stroke of a key the parts will be positioned, as represented in Fig. 2; the downward movement of the universal bar 68 having been effective to elevate the universal bar 66 to a position where any of the pawls 73 will coöperate therewith at the next down stroke of a key. When a key resumes its normal position from that shown in Fig. 2, after the first depression, the parts will be disposed as indicated in Fig. 3; the key having returned independently of the universal bars and the parts controlled thereby. The next down stroke of a key is effective to carry the pawl 73, carried by the associated key lever, into engagement with the universal bar 66, and a continued downward movement of the key lever depresses said universal bar 66 to the position shown in Fig. 4; at the same time elevating the universal bar 68 into operative position. This last mentioned down stroke of a key is effective to move the dog rocker to effect a rearward movement of a feed dog, back to the position shown in Fig. 1, and to afford a full letter space movement of the carriage. It will be understood that the universal bars and the constantly maintained connections between said universal bars and the movable feed element or member, which in the present instance is a feed dog 46, are normally disconnected from the key levers and that a depression of a key lever is effective to move these parts in one direction and then in the opposite direction at successive key strokes; that the only parts which need to be restored to normal position after each depression of a key are the key levers themselves and the actuating devices or pawls carried by them, so that these last mentioned parts may be quickly restored to normal position, enhancing the rapidity of operation; that the act of actuati-

ing the escapement mechanism to afford a letter space feed movement of the carriage is effective to set the parts, or certain of the parts, for the next operation, thereby rendering the escapement rapid in operation; that the first part of the stroke of each finger key is effected independently of the escapement mechanism, or the parts which constitute the train of connections from the universal bar to the movable feed dog, thus rendering the "touch" on the keys light at the first part of the stroke; that there are no such returning or restoring springs to overcome during the depression of a key as are ordinarily employed in escapements, which provides a light, easily operated escapement; that there is no backward and forward movement of the dog rocker and the parts connected therewith at each complete operation of a key but only a movement of the parts in one direction, so that there is no snapping of the parts back to normal position under spring pressure or the noise that would result therefrom; that a depression of any finger key is effective to positively move the parts in one direction to effect a letter feed movement of the carriage and that wear on the parts is therefore reduced one-half; that the up-stroke of a key is ineffective to move the universal bars, and the parts controlled thereby, which have been actuated by the down stroke of the key, so that any trembling movement of the finger key at the last portion of the key depression is ineffective to vibrate the dog rocker, which ordinarily would result in the carriage skipping or feeding improperly; and that therefore a positively acting, simple, efficient, light, rapid and reliable escapement mechanism is provided and one in which the wear on the parts is reduced one-half and in which the noise due to actuating the escapement is greatly reduced, if not entirely eliminated.

In order to regulate the timing of the "let-off" of the carriage at each actuation of a key, it is simply necessary to vary the overlap of the feed dog 46 on the teeth of the escapement wheels, by effecting a relative adjustment between the escapement wheels toward and away from each other in the manner hereinbefore described. The parts as shown in Fig. 1 are represented as they appear when the escapement wheels are adjusted farthest from each other to afford the quickest "let-off" of the carriage. This adjustment of the parts enables the carriage to be let off when the type bar reaches the position indicated in dotted lines in Fig. 1. The maximum adjustment of the escapement wheels toward each other is represented in the diagrammatic view shown in Fig. 7. By the arrangement of the parts shown in Fig. 7 the "let-off" is not effected until the type bar is close to the platen. It

will be understood that by adjusting the escapement wheels axially in the manner described toward and away from each other, the extent of overlap of the feed dog on the teeth of both escapement wheels is the same 70 so that the feed effected by a movement of the dog from, say, the escapement wheel 38 to the escapement wheel 34, is identically the same as that effected by a movement of the dog from the escapement wheel 34 to the 75 escapement wheel 38, and that this is true whatever the relative adjustment may be between the escapement wheels. This is clearly indicated by the diagrammatic view shown in Fig. 7. In this view the escapement wheels are shown in full lines at the extreme adjustment in one direction and in dotted lines at the extreme adjustment in the opposite direction. It will be understood from an inspection of the feed dog 46 85 and of its movement from the full to the dotted line position shown in this figure, that the extent of overlap between said dog and the teeth of the escapement wheels is the same for both wheels no matter what 90 the adjustment of said wheels may be.

The purpose of the adjusting means by which the dog rocker may be adjusted relatively to the arm 55 is to regulate the position of the feed dog with reference to the 95 escapement wheels after the screw stops 69 and 71 have been properly adjusted to regulate the positions and throw of the universal bars and connections controlled thereby.

For the purpose of my present invention 100 it is immaterial from certain aspects whether a single dog be employed to coöperate with two escapement racks or wheels, or whether a single escapement rack or wheel be provided to coöperate with two feed dogs. In 105 Figs. 8 and 9 I have shown a modified form of construction in which a single escapement wheel 82 is provided, and in which the teeth are so spaced and the parts so arranged that a movement of the wheel corresponding to 110 one-half the distance from one tooth to the next of the wheel, affords a full letter space movement of the carriage, as will herein-after appear. This escapement wheel is or may be operatively connected to the escapement wheel shaft 28^b by the usual pawl 83 and ratchet 84, to afford a movement of the carriage from left to right independently of the escapement wheel. The dog rocker 48^a is bifurcated at its upper end to provide two 115 arms 85. Two feed dogs 86 and 87 are received between the arms 85; each dog being threaded on an adjusting member 88 which is in the nature of a spindle pivoted on trunnions 89 in bearing openings in the arms 85. The adjusting member 88 is provided with right and left-hand screw threads 90 and 91 which coöperate with the dogs 87 and 86 respectively; said dogs being interiorly threaded in the 120 125 130

body portions thereof for coöperation with the right and left-hand threads of the member 88. One of the trunnions 89 is extended beyond the associated arm 85 and is provided with a screw driver nick 92, which affords a turning movement of the member 88 to effect a relative adjustment between the feed dogs toward and away from each other transversely of the plane of the escapement wheel. From an inspection of Fig. 8 it will be observed that the upwardly extending engaging projections of the feed dogs 86 and 87 are arranged out of register with each other and are separated sufficiently to afford a full letter-space movement of the carriage in the "drop" of a tooth of the escapement wheel from one dog to the other. This separation of the dogs also provides ample clearance for the movement of the dogs transversely of the escapement wheel. It will be understood that a depression of the finger key is effective to move the dog rocker in one direction and that the next depression of the finger key is effective to move the dog rocker in the opposite direction, and that each of these movements of the dog rocker is effective to move one of the dogs out of coöperation with the escapement wheel and to bring the other dog into the path of the next on-coming tooth of the wheel to afford a full letter space movement of the carriage. The effect of adjusting the two feed dogs 86 and 87 toward and away from each other is the same exactly as effecting a relative adjustment of the escapement wheels toward and away from each other in the previously described construction.

One of the arms 85 hereinbefore referred to is preferably formed as a separate plate 93 secured to the dog rocker by a screw 94. This is to enable the parts to be readily assembled or taken down.

What I claim as new and desire to secure by Letters Patent, is:—

1. In a typewriting machine, the combination of a power driven carriage; coöperative escapement members one of which is movable back and forth transversely of the other; finger keys; and means intermediate said finger keys and said movable escapement member for moving the latter either back or forth in one direction at each complete operation of a key, said means comprising two universal bars, and actuating means coöperative with said universal bars.

2. In a typewriting machine, the combination of a power driven carriage; coöperative escapement members one of which is movable back and forth transversely of the other; finger keys; and means intermediate said finger keys and said movable escapement member for moving the latter either back or forth in one direction at each complete operation of a key, said means com-

prising two universal bars, and means actuated by said keys for alternately depressing said universal bars at successive key operations.

3. In a typewriting machine, the combination of a power driven carriage; coöperative escapement members one of which is movable back and forth transversely of the other; finger keys; and means intermediate said finger keys and said movable escapement member for moving the latter either back or forth in one direction at each complete operation of a key, said means comprising two universal bars, a single carrier for said bars, said carrier being pivoted intermediate the bars, and means coöperative alternately with said bars to actuate them.

4. In a typewriting machine, the combination of a power driven carriage; coöperative escapement members one of which is movable back and forth transversely of the other; finger keys; and means intermediate said finger keys and said movable escapement member for moving the latter either back or forth in one direction at each complete operation of a key, said means comprising two universal bars, and means by which said finger keys are rendered operative alternately on first one and then the other of said universal bars, the actuation of one bar by a finger key rendering the other universal bar operative at the next key operation.

5. In a typewriting machine, the combination of a power driven carriage; coöperative escapement members one of which is movable back and forth transversely of the other; finger keys; and means intermediate said finger keys and said movable escapement member for moving the latter either back or forth in one direction at each complete operation of a key, said means comprising two universal bars, key controlled means for actuating said universal bars, and means by which the actuation of one of said universal bars is effective to bring the other universal bar into coöperative relation with said key controlled actuating means therefor.

6. In a typewriting machine, the combination of a power driven carriage; coöperative escapement members one of which is movable back and forth transversely of the other; finger keys; and means intermediate said finger keys and said movable escapement member for moving the latter either back or forth in one direction at each complete operation of a key, said means comprising two universal bars, and means by which one universal bar is elevated when the other is depressed.

7. In a typewriting machine, the combination of a power driven carriage; coöperative escapement members one of which is movable back and forth transversely of the

- other; finger keys; and means intermediate said finger keys and said movable escapement member for moving the latter either back or forth in one direction at each complete operation of a key, said means comprising two universal bars, key actuated devices, one or more of said devices being controlled by each of said finger keys, and means which render said key actuated devices operative alternately first on one and then on the other of said universal bars at successive operations of said keys.
8. In a typewriting machine, the combination of a power driven carriage; coöperative escapement members one of which is movable back and forth transversely of the other; finger keys; and means intermediate said finger keys and said movable escapement member for moving the latter either back or forth in one direction at each complete operation of a key, said means comprising two universal bars, levers with which said finger keys are connected, pawls carried by said levers, and means by which said pawls are rendered alternately operative first on one and then on the other of said universal bars.
9. In a typewriting machine, the combination of a power driven carriage; coöperative escapement members one of which is movable back and forth transversely of the other; finger keys; and means intermediate said finger keys and said movable escapement member for moving the latter either back or forth in one direction at each complete operation of a key, said means comprising two universal bars, key levers which carry said finger keys, pawls which are carried by said key levers, springs which tend to maintain said pawls in fixed relation to the key levers which carry them, and means by which said pawls are rendered operative alternately first on one and then on the other of said universal bars.
10. In a typewriting machine, the combination of a power driven carriage; coöperative escapement members one of which is movable back and forth transversely of the other; finger keys; and means intermediate said finger keys and said movable escapement member for moving the latter either back or forth in one direction at each complete operation of a key, said means comprising two universal bars, key levers which carry said finger keys, pawls which are carried by said key levers, springs which tend to maintain said pawls in a fixed relation to the key levers which carry them, and means for moving one universal bar into coöperative relation with a pawl on each key lever when the other universal bar is actuated.
11. In a typewriting machine, the combination of a power driven carriage; coöperative escapement members one of which is movable back and forth transversely of the other; finger keys; and means intermediate said finger keys and said movable escape-
- other; finger keys; and means intermediate said finger keys and said movable escapement member for moving the latter either back or forth in one direction at each complete operation of a key, said means comprising two universal bars, key controlled actuating devices, and means for swinging one universal bar into the path of the actuating devices when the other universal bar is swung out of the path of the actuating devices.
12. In a typewriting machine, the combination of a power driven carriage; coöperative escapement members one of which is movable back and forth transversely of the other; finger keys; and means intermediate said finger keys and said movable escapement member for moving the latter either back or forth, said means comprising two universal bars, and means for alternately actuating first one and then the other of said universal bars and by which each universal bar is moved only at a down stroke of a key.
13. In a typewriting machine, the combination of a power driven carriage; coöperative escapement members one of which is movable back and forth transversely of the other; finger keys; and means intermediate said finger keys and said movable escapement member for moving the latter either back or forth, said means comprising two universal bars, a single carrier for said bars, said carrier being pivoted intermediate said bars, and means coöperative alternately with said universal bars at successive key operations.
14. In a typewriting machine, the combination of a power driven carriage; coöperative escapement members one of which is movable back and forth transversely of the other; finger keys; and means intermediate said finger keys and said movable escapement member for moving the latter either back or forth, said means comprising two universal bars, and means by which the actuation of one universal bar by a key operation is effective to render the other universal bar operative at the next key operation.
15. In a typewriting machine, the combination of a power driven carriage; coöperative escapement members one of which is movable back and forth transversely of the other; finger keys; and means intermediate said finger keys and said movable escapement member for moving the latter either back or forth, said means comprising two universal bars, and means by which one universal bar is elevated when the other is depressed.
16. In a typewriting machine, the combination of a power driven carriage; coöperative escapement members one of which is movable back and forth transversely of the other; finger keys; and means intermediate said finger keys and said movable escape-

- ment member for moving the latter either back or forth, said means comprising two universal bars, key actuated devices, one or more of said devices being controlled by 5 each of said finger keys, and means which render said key actuated devices operative alternately first on one and then on the other of said universal bars at successive operations of said keys.
- 10 17. In a typewriting machine, the combination of a power driven carriage; coöperative escapement members one of which is movable back and forth transversely of the other; finger keys; and means intermediate 15 said finger keys and said movable escapement member for moving the latter either back or forth in one direction at each complete operation of a key, said means comprising universal bar mechanism, and means controlled by said finger keys to move said universal bar mechanism alternately first in one direction and then in the opposite direction at successive key operations.
18. In a typewriting machine, the combination of finger keys; a power driven carriage; escapement mechanism therefor, a universal bar; and means by which said universal bar is moved in but one direction at each complete operation of a finger key.
- 30 19. In a typewriting machine, the combination of finger keys; a power driven carriage; escapement mechanism therefor, a universal bar free from spring pressure, and key controlled means for moving said universal bar in opposite directions at successive key operations, each complete key operation moving the universal bar in but one direction.
20. In a typewriting machine, the combination of finger keys; a power driven carriage; coöperative escapement devices, one of which is movable transversely of the other under control of said finger keys; and intermediate actuating connections between 45 said finger keys and said movable escapement member, said connections including a universal bar, constantly maintained connections between said universal bar and said movable escapement member, and means by 50 which the finger keys are rendered effective to move said universal bar alternately first in one direction and then in the opposite direction at successive key operations.
- 55 21. In a typewriting machine, the combination of finger keys; a power driven carriage; coöperative escapement devices one of which is movable transversely of the other under control of said finger keys; and intermediate actuating connections between 60 said finger keys and said movable escapement member, said connections including a universal bar free from spring pressure, constantly maintained connections between said universal bar and said movable escapement member, and means by which the fin-

ger keys are rendered effective at the down stroke only to move said universal bar alternately first in one direction and then in the opposite direction at successive key operations.

70 22. In a typewriting machine, the combination of finger keys; a power driven carriage; coöperative escapement devices one of which is movable transversely of the other under control of said finger keys; and intermediate actuating connections between said finger keys and said movable escapement member, said connections including a rocker, a universal bar, a constantly maintained connection between said universal 75 bar and rocker, and means operative only at the down strokes of the keys for moving said universal bar first in one direction and then in the opposite direction at successive key operations, each key operation moving the universal bar in but one direction.

23. In a typewriting machine, the combination of a power driven carriage; escapement mechanism; key levers; and means controlled by the key levers for controlling 90 said escapement mechanism, said means comprising two pawls carried by each of said key levers, two universal bars, and means by which the two pawls on each key lever are rendered alternately operative on 95 the respective universal bars with which they coöperate.

24. In a typewriting machine, the combination of a power driven carriage; escapement mechanism; key levers; and means 100 controlled by the key levers for controlling said escapement mechanism, said means comprising two pawls carried by each of said key levers, two universal bars, a rocker controlled thereby, and means by which the 105 two pawls on each key lever are rendered alternately operative on the respective universal bars with which they coöperate, whereby the rocker is alternately rocked first in one direction and then in the opposite direction at successive key depressions.

25. In a typewriting machine, the combination of a power driven carriage; escapement mechanism; key levers; and means controlled by the key levers for controlling 115 said escapement mechanism, said means comprising two spring pressed pawls carried by each of said key levers, two universal bars connected to move in unison but in opposite directions, a rocker controlled thereby and free from spring pressure, and means by which the two pawls on each key lever are rendered alternately operative on the respective universal bars with which they coöperate.

120 26. In a typewriting machine, the combination of a carriage; escapement mechanism therefor comprising an escapement wheel and a feed dog, a single movement of the feed dog in one direction affording a com- 130

plete letter space movement of the carriage; finger keys; means intermediate said finger keys and dogs for effecting a movement of said feed dog alternately in one direction and then in the other at successive operations of the keys, each complete operation of a key effecting a movement of the dog in one direction, said means comprising two universal bars which are operated alternately at successive key operations.

27. In a typewriting machine, the combination of a carriage; escapement mechanism therefor comprising a feed rack and a dog, one of said feed rack and dog members being movable relatively to the other; finger keys; means intermediate said keys and said movable member for effecting a movement of said movable member in one direction only at each complete actuation of a key; successive operations of the keys effecting a movement of said movable member first in one direction and then in the opposite direction, said means comprising a universal bar, and means by which said universal bar is moved in but one direction at each complete actuation of a key.

28. In a typewriting machine, the combination of a carriage; escapement mechanism therefor comprising two coöperative escapement members, and a rocker which carries one of said escapement members; finger keys; means intermediate said finger keys and rocker for moving the rocker alternately first in one direction and then in the other at successive operations of said finger keys; a complete operation of each finger key effecting only a single movement of the rocker in one direction, said means comprising a universal bar which is moved only at the down strokes of the keys.

29. In a typewriting machine, the combination of a power driven carriage; escapement mechanism therefor comprising two coöperative escapement members one movable back and forth relatively to the other and free to remain in either of the two back and forth positions to which it may be moved; finger keys; means controlled by said finger keys for moving said movable escapement member alternately first to one of said positions and then to the other, said means comprising a universal bar free to remain in the position to which it may be moved at each key depression.

30. In a typewriting machine, the combination of a power driven carriage; escapement mechanism therefor; finger keys; means controlled by said finger keys for controlling a member of said escapement mechanism, said controlling means comprising two sets of key operated actuating devices that move in the same direction at the down strokes of the keys, two universal bars, and means by which the universal

bars are brought alternately into coöperative relation with the associated set of actuating devices.

31. In a typewriting machine, the combination of finger keys; a power driven carriage; coöperative escapement devices, one of which is movable transversely of the other under control of the keys; and key controlled means for controlling said movable escapement members, said means comprising two actuating devices movable in the same direction at each operation of a key, and means coöperative alternately with first one and then the other of said actuating devices to move the said movable escapement member.

32. In a typewriting machine, the combination of a power driven carriage; two escapement wheels; a single feed dog coöperative therewith; a dog rocker which is free to be moved back and forth and to remain in either of the back and forth positions to which it may be moved; printing keys; and means intermediate said printing keys and dog rocker for moving the latter in but one of said back and forth directions at each complete operation of a key, said means comprising a universal bar, and means by which the universal bar is moved in but one direction at each complete operation of a key.

33. In a typewriting machine, the combination of a power driven carriage; two escapement wheels; a single feed dog coöperative therewith; a dog rocker which is free to be moved back and forth and to remain in either of the back and forth positions to which it may be moved; printing keys; and means intermediate said printing keys and dog rocker for moving the latter in but one of said back and forth directions at each complete operation of a key, said means comprising two universal bars, and means by which one universal bar is moved into operative position by the movement of the other universal bar out of operative position.

34. In a typewriting machine, the combination of a power driven carriage; two escapement wheels; a single feed dog coöperative therewith; a dog rocker which is free to be moved back and forth and to remain in either of the back and forth positions to which it may be moved; printing keys; and means intermediate said printing keys and dog rocker for moving the latter in but one of said back and forth directions at each complete operation of a key, said means comprising two universal bars and means whereby successive key strokes are operative to alternately move first one and then the other of said universal bars.

35. In a typewriting machine, the combination of a power driven carriage; two escapement wheels which are fixed to turn

- together and which afford a full letter space movement of the carriage at each movement of the wheels from one tooth on one wheel to the next tooth on the other wheel; a single dog which coöperates with said escapement wheels; a dog rocker which carries said dog and by which it is moved back and forth transversely through said wheels, said rocker being free to re-
 5 main in either of the back and forth positions to which it may be moved; printing keys; and means controlled thereby for moving the rocker back and forth and for moving it to but one of said back and forth
 10 positions at each complete operation of a printing key, said moving means including two universal bars, and means by which said universal bars are alternately operated upon at successive key operations.
 15 36. In a typewriting machine, the combination of a power driven carriage; two escapement wheels therefor, said wheels being connected to turn together; a dog rocker; a single dog carried by said dog rocker and
 20 affording a full letter space movement of the carriage at each back or forth movement of the dog rocker; finger keys; means controlled by said finger keys for moving said dog rocker, said means including universal
 25 bar mechanism, and means by which the universal bar mechanism is moved in but one direction at each complete operation of a key and a corresponding movement is transmitted to the dog rocker.
 30 37. In a typewriting machine, the combination of a carriage; feed mechanism therefor including two coöperative members, one of which comprises two elements that coöperate alternately with the other member
 35 to afford a feed of the carriage; and means for effecting an adjustment of both said elements toward and away from each other.
 40 38. In a typewriting machine, the combination of a carriage; feed mechanism therefor including two coöperative members, one of which comprises two elements that coöperate alternately with the other member to afford a feed of the carriage; finger keys; means under control of the finger keys for
 45 moving one of said escapement members transversely of the other; and means for effecting an adjustment of both said elements toward and away from each other.
 50 39. In a typewriting machine, the combination of a carriage; carriage feed mechanism including two feed members carried by the same part of the machine and arranged side by side; and means for effecting an adjustment of said members toward or
 55 away from each other in substantially parallel planes.
 60 40. In a typewriting machine, the combination of a carriage; carriage feed mechanism including two parallel feed racks; and
 65 means for effecting a relative adjustment of

said racks toward or away from each other in parallel planes.

41. In a typewriting machine, the combination of a carriage; carriage feed mechanism including two parallel escapement wheels fixed to turn together; and means for effecting an adjustment of said escapement wheels toward and away from each other in parallel planes. 70

42. In a typewriting machine, the combination of a power driven carriage; escapement mechanism therefor including two parallel escapement wheels fixed to rotate together; and a single dog coöperative with said escapement wheels to afford a full letter space movement of the carriage at each movement of the dog from engagement with a tooth of one escapement wheel into engagement with the next tooth of the other escapement wheel; and means for effecting an adjustment of said escapement wheels toward and away from each other. 75 80 85

43. In a typewriting machine, the combination of a power driven carriage; escapement mechanism therefor comprising two escapement wheels; a single dog coöperative therewith; and means for effecting an adjustment of said escapement wheels toward and away from each other, said adjusting means comprising a right and left hand screw. 90 95

44. In a typewriting machine, the combination of a carriage; feed mechanism therefor comprising two feed devices arranged side by side; and an adjustable member on which said devices are mounted and by which they may be simultaneously adjusted toward and away from each other to different set positions. 100

45. In a typewriting machine, the combination of a carriage; feed mechanism therefor comprising two feed devices arranged side by side; and an adjustable spindle having right and left-hand screw threads with which said devices coöperate and by which they may be simultaneously adjusted toward and away from each other to different set positions. 105 110

46. In a typewriting machine, the combination of a carriage; and feed mechanism therefor including a pivoted rocker having an arm adjustably fixed thereto for connection with the means for actuating said rocker, and a cam for effecting an adjustment of said rocker relatively to the arm. 115 120

47. In a typewriting machine, the combination of a carriage; and escapement mechanism therefor including a rocker, a shaft for said rocker, an actuating arm loose upon said shaft, and adjustable means for connecting the actuating arm to the rocker. 125

48. In a typewriting machine, the combination of a key lever; two pawls carried by said key lever; spring means for maintaining the said pawls normally fixed with ref. 130

erence to said key lever; universal bar mechanism controlled by said pawls; and carriage escapement mechanism controlled by said universal bar mechanism.

- 5 49. In a typewriting machine, the combination of finger keys; a power driven carriage; escapement mechanism therefor comprising three coöperating toothed escapement devices, one of which coöperates with
 10 the other two to control the movement of the carriage at the operation of the finger keys; and means for effecting an adjustment of said two escapement devices toward and away from each other to regulate the extent of overlapping engagement between said toothed escapement member.
50. In a typewriting machine, the combination of finger keys; a power driven carriage; escapement mechanism therefor comprising three coöperating toothed escapement devices, one of which coöperates with the other two to control the movement of the carriage at the operation of the finger keys; and means for effecting a simultaneous
 20 adjustment of said two escapement devices toward and away from each other to equal extents to regulate the extent of overlapping engagement between said toothed escapement members and to assure the same extent
 25 of overlap between the single toothed escapement device and each of the other two devices.
51. In a typewriting machine, the combination of finger keys; a power driven carriage; escapement mechanism therefor comprising a toothed double escapement device, and a coöperative toothed single escapement device; and means for effecting a corresponding adjustment of both members of
 30 said double escapement device toward and away from each other and for retaining the said members in the relative positions to which they are adjusted, whereby the overlapping engagement between both members

of the double escapement devices and said single device may be varied and the variation in overlap effected by each adjustment of said adjustable means will be the same on both members of said double escapement device.

52. In a typewriting machine, the combination of finger keys; a power driven carriage; escapement mechanism therefor comprising coöperating toothed escapement devices two of which are engaged by a third device, and adjustable means operable at will for effecting a variation in the overlapping engagement between said members and by which any variation in the overlap between the said third device and one of the said two devices produces a corresponding overlap between the said third device and the other of said two devices.

53. In a typewriting machine, the combination of finger keys; a power driven carriage; escapement mechanism therefor comprising coöperating toothed escapement devices two of which are alternately engaged by a third device at successive key depressions to afford a full letter space movement of the carriage at each complete operation of a key; and adjustable means operable at will for effecting a variation in the overlapping engagement between said members and by which any variation in the overlap between the said third device and one of the said two devices produces a corresponding overlap between the said third device and the other of said two devices.

Signed at the borough of Manhattan, city 80 of New York, in the county of New York, and State of New York, this 12th day of November, A. D. 1910.

JOHN WALDHEIM.
